(57) **CLAIM**

The ornamental design for an electronic device with graphical user interface, as shown and described.

DESCRIPTION

FIG. 1 is a front view of electronic device with graphical user interface, showing the claimed design;

FIG. 2 is a front view of a second embodiment thereof;
FIG. 3 is a front view of the first embodiment shown on an alternate electronic device. The graphical user interface of FIG. 2 may be similarly applied thereto; and,

FIG. 4 is a front view of the first embodiment shown on another alternate electronic device. The graphical user interface of FIG. 2 may be similarly applied thereto.

The broken lines in the figures show an electronic device and form no part of the claimed design.
